UNITED STATES PATENT OFFICE.

JOSEPH BENOSCH, OF AMSTERDAM, NEW YORK, ASSIGNOR TO KLAUDER-WELDON
DYEING MACHINE COMPANY, OF AMSTERDAM, NEW YORK, A CORPORATION OF
NEW YORK.

DYEING APPARATUS.

1,120,644.

Specification of Letters Patent.

Patented Dec. 8, 1914.

Application filed December 13, 1913. Serial No. 806,372.

To all whom it may concern:

Be it known that I, JOSEPH BENOSCH, a citizen of the United States, residing at Amsterdam, in the county of Montgomery and State of New York, have invented certain new and useful Improvements in Dyeing Apparatus, of which the following is a full, clear, and exact description, such as will enable others skilled in the art to which it appertains to make and use the same.

This invention relates to dyeing apparatus.

One of the objects thereof is to provide simple and practical apparatus of the above type in which the parts are conveniently manipulated in loading and unloading the machine.

Another object is to provide reliable and effective apparatus for locking supporting members in operative position.

Another object is to reduce the number of springs in apparatus of the above type without sacrificing security of position of the parts or ease of manipulation.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, in which is shown one of various possible embodiments of this machine, Figure 1 is a side elevation of a carrying member and associated parts; Fig. 2 is a vertical section showing a pair of carrying members mounted upon their shaft; Fig. 3 is a vertical section of a portion of a carrying member with the locking devices closed; Fig. 4 is a side elevation of the parts shown in Fig. 3 with the locking devices open; Fig. 5 is a detail elevation of another portion of the carrying member; Fig. 6 is a sectional view taken substantially along the line $x-x$ of Fig. 5; and Fig. 7 is a sectional view taken substantially along the line $y-y$ of Fig. 4 showing the parts upon a larger scale.

Similar reference characters refer to similar parts throughout the several views.

Referring now to Fig. 2 of the drawings,

there is shown a supporting shaft 1 upon which are mounted the carrying members or spiders 2 and 3. Upon the members 2 are a series of sockets or cups 4 which are rotatable as by means of the star wheels diagrammatically indicated at 5. These sockets are of squared conformation to fit the supporting sticks 6, the free ends of which are provided with a rounded extension 7 resting within round sockets 8 and corresponding openings passing through the spider 3. These sticks 6 are mounted at equal distances from shaft 1 about the circumference of the rotary carrying members 2 and 3. Upon the side of the carrier 3 away from the sticks there are slidably mounted a plurality of locking slides 9, as indicated in Fig. 1 of the drawings. These locking slides, more clearly shown in Figs. 3 and 4, are provided with openings which in one position of the slide exactly register with the cups 8 and permit the sticks 6 to be moved longitudinally to such an extent as to release their squared ends from the cups 4. If the slide, however, which is fitted between guides 10 and the flange 11 be moved into the position shown in Fig. 3 of the drawings it closes the ends of these openings and holds the sticks 6 against longitudinal movement, thus locking them in operative position. The slide is securely held against lateral movement by means of the projecting lugs 12 fitting in slots 13 in the flange 11 and is held in its locking or releasing position by means of a set screw 14 which passes through a slot and is tapped within a portion of the slide. About the inner portion of the carriers 2 and 3, is another set of supporting sticks 15. The locus of the centers of the sticks of this set lies in a path substantially concentric with the shaft, and one end of each stick is journaled in a cup 16, as shown in Fig. 2 of the drawings. The remaining ends of these sticks rest in cups 17, upon the member 3, and there are provided in the latter member, openings 18 registering with these cups and permitting a movement, unless otherwise prevented such as will release the ends from cups 16 and allow the removal of the sticks. Mounted upon the outer surface of the annular member 19 on which the cups 17 are formed is an oscillating ring 20 which is guided by flanges 21 and held in position as

by the rivet head 22. This slide 20 may be oscillated to a slight extent about the axis of shaft 1 so as to bring the openings 23 therein out of register with the openings 18 and thus lock the sticks 15 in operative position in a manner analogous to that in which the outer sticks 6 are secured. The ring 20 is manipulated by means of a projecting handle 24 which is provided with a perforation 25 coacting with similar perforations 26 in a locking plate 27 whereby the handle may be locked by a pin in either of its extreme positions, the latter being limited by means of the slot 28 coacting with the rivet head 22. This ring extends entirely about the annular member 19, but it will be noted that the outer locking slides each coact with a set or group of sticks, five of these sticks being shown in this illustrative embodiment as in Fig. 1.

It is to be understood that the term "locking", or its equivalent, is used throughout in a broad sense as denoting any securing action by which the parts thus defined are held in position.

In the use of this apparatus the pairs of sticks are inserted one pair at a time in the machine, the inner stick being first placed in sockets 16 and 17, and the corresponding outer stick having its end first thrust within socket 8, then moved longitudinally to permit it to be set within the corresponding socket 4. When a group of these outer sticks is thus placed in position, a corresponding locking slide is moved into its operative position, shown in Fig. 3, and the sticks are thus held against longitudinal movement and cannot become displaced in use, the locking slide being gripped against the flange 11 by the screw 14. The machine is thus filled, and when all of the inner sticks are in position the handle 24 is moved to displace the openings in ring 20 with respect to the openings 18 and thus lock the inner sticks. It will thus be seen that both sets of sticks are securely held in position and the use of springs done away with, and that the ease of loading and unloading the machine is much enhanced and the actual time required for such action reduced.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In dyeing apparatus or the like, in combination, a rotary supporting stick, means for supporting one end of said stick, a mem-

ber in which the other end of said stick rests, a slide adapted to lock said stick in operative position, and means adapted to secure said slide in locking position.

2. In dyeing apparatus or the like, in combination, a plurality of supporting sticks, and movable means adapted simultaneously to lock said sticks in operative position.

3. In dyeing apparatus or the like, in combination, a carrying member, a supporting stick having one end resting in said member, a slide upon said carrying member adapted to lock said stick in operative position, and means adapted to secure said slide in locking position.

4. In dyeing apparatus or the like, in combination, a carrying member, a plurality of supporting sticks having their ends supported by said member, and means upon said carrying member adapted simultaneously to lock said sticks in operative position.

5. In dyeing apparatus or the like, in combination, a pair of rotary carrying members, a plurality of supporting sticks between said members and carried by the outer portions of said members, and means adapted to lock and release said sticks in groups.

6. In dyeing apparatus or the like, in combination, a pair of rotary carrying members, a plurality of supporting sticks between said members and carried by the outer portions of said members, and a plurality of locking devices upon one of said members, each of which is adapted to simultaneously lock a plurality of said sticks in operative positions.

7. In dyeing apparatus or the like, in combination, a pair of rotary carrying members, a plurality of rotary supporting sticks between said members, each of said sticks having one end mounted upon one of said members and the other end adapted to be moved longitudinally within the other of said members, and a slide upon said last member adapted to be moved into a position to prevent longitudinal motion of said sticks.

8. In dyeing apparatus or the like, in combination, a pair of rotary carrying members, a plurality of rotary supporting sticks, each of which has one end resting within a socket upon one of said supporting members and the other end slidably fitted in an opening extending transversely through the other of said carrying members, and a slide upon the side of said last member away from said sticks mounted for movement into alternative positions, in one of which it will permit said sticks to be moved longitudinally to release their ends from said sockets and in the other of which it will prevent said movement.

9. In dyeing apparatus or the like, in combination, a pair of rotary carrying members, two sets of coacting supporting sticks mounted upon and between said members,

the locus of the centers of each set lying in a path substantially concentric with the axis thereof, and separate means respectively adapted to simultaneously lock a plurality 5 of sticks of each set.

10. In dyeing apparatus or the like, in combination, a pair of rotary carrying members, a plurality of rotary sticks mounted between and supported by said members intermediate their axis and circumferential 10 portions, means upon one of said members adapted to receive and journal one end of each of said sticks, means upon the other of said members adapted to receive the other 15 ends of said sticks and permit them to be slid out of engagement with said first member, and a slide extending about the side of said last carrying member away from said sticks and mounted for movement into a position in which it will lock all of said sticks 20 in operative position.

11. In dyeing apparatus or the like, in combination, means for supporting one end 25 of a yarn stick, a member in which the other end of said stick rests, and means adapted to lock said stick in operative position comprising a member beyond which the end of the stick may pass when introduced and adapted to lie transversely opposite the end 30 of the stick when in locking position.

12. In dyeing apparatus or the like, in combination, a pair of revoluble stick-supporting members, and means adapted to lock a stick in operative position therein, comprising a movable member beyond which the end of the stick may pass when introduced 35

and adapted to lie transversely opposite the end of the stick when in locking position.

13. In dyeing apparatus or the like, in combination, a pair of revoluble stick-supporting members, and means adapted to lock a stick in operative position therein, comprising an arcuate member beyond which the end of the stick may pass when introduced and adapted to lie transversely opposite the end of the stick when in locking 40 45 position.

14. In dyeing apparatus or the like, in combination, a pair of revoluble stick-supporting members, and means adapted to lock a stick in operative position therein, comprising a movable member beyond which the end of the stick may pass when introduced and adapted to lie transversely opposite the end of the stick when in locking 50 55 position.

15. In dyeing apparatus or the like, in combination, a pair of revoluble stick-supporting members, and means adapted to lock a stick in operative position therein, comprising an arcuate movable member beyond which the end of the stick may pass when introduced and adapted to lie beyond the plane of the end of the stick when in locking 60 65 position.

In testimony whereof I affix my signature, in the presence of two witnesses.

JOSEPH BENOSCH.
